Filed Sept. 24, 1970, Ser. No. 25,179

Term of patent 14 years

Int. Cl. D26—05

U.S. Cl. D48—20

FIG. 1 is a side elevational view of a table lamp showing my new design;

FIG. 2 is a front elevational view thereof;

FIG. 3 is a rear elevational view thereof;

FIG. 4 is an enlarged side elevational view thereof, the lamp being fragmentarily shown for convenience of illustration;

FIG. 5 is a top plan view of the lamp as shown in FIG. 4.

The characteristic features of my design reside in the configuration of the pole supported lamphead.

I claim:

The ornamental design for a table lamp, substantially as shown and described.
